UNITED STATES PATENT OFFICE.

WILLIAM S. GRAFTON, OF STEUBENVILLE, OHIO, AND EDWIN C. EWING AND ALEXANDER GLASS, OF WHEELING, WEST VIRGINIA, ASSIGNEES TO THE WHEELING CORRUGATING COMPANY, OF WHEELING, WEST VIRGINIA.

DESIGN FOR A METALLIC FINISHING-PLATE.

SPECIFICATION forming part of Design No. 22,345, dated April 11, 1893.

Application filed March 14, 1893. Serial No. 465,972. Term of patent 14 years.

To all whom it may concern:

Be it known that we, WILLIAM S. GRAFTON, residing at Steubenville, in the county of Jefferson and State of Ohio, and EDWIN C. EWING and ALEXANDER GLASS, residing at Wheeling, in the county of Ohio and State of West Virginia, citizens of the United States, have invented and produced a new and original Design for Metallic Finishing-Plates for Buildings, of which the following is a specification, reference being had to the accompanying drawing, forming part thereof, which shows a metallic finishing-plate or ceiling-plate designed according to our invention.

Our design consists of a square or rectangular metallic finishing plate A, having at each of its edges a rib b, and at each of its corners, a curved projection c, which is concave and within which is a knob or projection d. The diagonally opposite corners of the plate are

connected by ribs e, which cross each other at the center of the plate.

The essential feature of our design is a metallic finishing plate having ribs at its edges, and a curved projection at each of its corners, the diagonally opposite corners of the plates being connected by ribs which cross each other at the center. 25

We claim—

The design for a metallic finishing plate 30 herein shown and described.

In testimony whereof we have hereunto subscribed our names.

WILLIAM S. GRAFTON.
EDWIN C. EWING.
ALEXANDER GLASS.
